AUTOGRAM

Michael Warner, Chicago, Ill.

Application October 28, 1941, Serial No. 416,889

4 Claims. (Cl. 40—140)

This invention relates to autograms and has for an object to provide a decorative identifying automobile accessory displaying the owner's initials on the side of the hood, radiator, or other desired part of the automobile.

A further object is to provide a device of this character in which the initials are displayed on respective colored or uncolored "jewels" of the type used on roadway signs and other places, the jewels being held in spring clips in openings in the front of a casing, through which openings when the jewels are removed, the securing means of the casing may be removed and applied by a tool inserted through the openings.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawing forming a part of this specification:

Figure 1 is a front elevation of an autogram constructed in accordance with the invention.

Figure 2 is a longitudinal sectional view of the autogram taken on the line 2—2 of Figure 1, showing one of the jewels removed.

Figure 3 is a cross sectional view of the autogram taken on the line 3—3 of Figure 1.

Figure 4 is a plan view of one of the initials displaying jewels showing the attaching spring clips therefor.

Figure 5 is a rear elevation of the device.

Figure 6 is a rear elevation of one of the initials displaying jewels.

Figure 7 is a rear elevation of a jewel of square contour instead of circular.

Figure 8 is a front elevation of a modified form of the autogram, showing the same in the shape of a shield.

Figure 9 is a front elevation of another modified form of the autogram, showing the same in the shape of a triangle having space for a manufacturer's identifying mark below the jewels.

Referring now to the drawing in which like characters of reference designate similar parts in the various views, autogram comprises an elongated rectangular casing having its front wall 10,

end walls 11, and top and bottom walls 12 and 13, formed integrally and detachably connected to its rear wall or attaching plate 14. The end, top and bottom walls of the casing are inclined and provided at their rear edges with respective flanges 15, 16 and 17, best shown in Figure 5. The edges of the rear wall 14 are clamped between the inclined walls 11, 12 and 13 and the flanges 15, 16 and 17 to secure the parts of the casing in assembled relation, as best shown in Figures 2 and 3.

The front wall 10 is provided with openings 18 for the reception of jewels 19, each bearing an initial of the automobile owner.

Each jewel is provided with a circumferential frame 20 adapted to overlap the front face of the front wall 10. A plurality of reversely curved spring clips 21 are secured to the frame and are adapted to be inserted through the openings 18 and spring over the rear face of the front wall 10, as best shown in Figures 2 and 3 to removably secure the jewels to the casing.

The rear wall or securing plate 14 is provided with openings 22 to receive screws 23 which may be engaged in a part 24 of the automobile, such as a door, hood, radiator, or other desired part of the automobile. The openings 22 are arranged directly in rear of the jewel receiving openings 18 so that when a jewel is removed, the opening 18 will expose the openings 22 so that a tool may be inserted for applying and removing the screws 23.

Each jewel may be circular, as shown in Figure 6, or may be square in contour, as shown in Figure 7, in the latter case, of course, the peripheral frame 24 being square and the spring clips 25 being disposed opposite each other similar to the spring clips of the circular type of jewel.

The frame, instead of being rectangular in contour may be a shield in contour, as shown at 26 in Figure 8, and the jewels 27 may be arranged in a vertical row on the longitudinal center line of the front wall of the autogram.

Still another modification is shown in Figure 9, in which the frame 28 is triangular in form and is provided with a rectangular row of jewels 29 in the front wall extending across the wide end 50 of the frame so that a triangular space 30 remains below the row of jewels to display the automobile manufacturer's embossing or identifying emblem or insignia.

From the above description it is thought that the construction and operation of the invention

will be fully understood without further explanation.

What is claimed is:

1. An autogram comprising a casing having its front, end, top and bottom walls formed integrally, the end, top and bottom walls being inclined and provided at their rear edges with flanges, a rear wall having its edges clamped between said inclined walls and said flanges to secure the parts of the casing in assembled relation, the front wall being provided with openings, initialed jewels in said opening secured to the front wall by spring clips engaged over the rear face of the front wall, there being openings in the rear wall for the passage of securing elements located opposite the openings in the front wall to permit the casing to be secured in place by a tool inserted through the front wall openings to engage the securing elements.

2. The structure as of claim 1 and in which said spring clips are carried by a frame surrounding each jewel and overlapping the outer face of the front wall.

3. An autogram, comprising a rectangular cas-

ing formed of metal with the front wall connected to the rear wall by inclined end and side walls, the front wall being provided with openings, initialed jewels in said openings secured to the front wall by spring clips engaging over the rear face thereof, the rear wall having openings for the passage of securing elements opposite the openings in the front wall to permit the casing to be secured in place by a tool inserted through the front wall openings to engage the securing elements.

4. An autogram, comprising a rectangular casing, the front wall being provided with openings, initialed jewels in said openings secured to the front wall by spring clips engaging over the rear face thereof, the rear wall of the casing provided with openings opposite the openings in the front wall for the passage of securing elements therethrough, whereby a tool may be inserted through the openings in the front wall to engage the securing elements passing through the openings in the rear wall.

MICHAEL WARNER.
